PRISMATIC TELESCOPE FOR TELEPHOTOGRAPHY OR SIMILAR USES

Paul R. Maguire, Los Angeles, Calif., assignor to
David P. Bushnell, Altadena, Calif.

Filed Nov. 13, 1964, Ser. No. 82,592

Term of patent 14 years

(Cl. D57—1)

FIG. 1.

FIG. 2.

FIG. 3.

FIG. 4.

FIG. 1 is a side elevation view of a prismatic telescope for telephotography or similar uses, showing my new design;

FIG. 2 is a bottom plan view;

FIG. 3 is a left side view; and

FIG. 4 is a right side view.

I claim:

The ornamental design for a prismatic telescope for telephotography or similar uses, as shown.
